UNITED STATES PATENT OFFICE.

WILLIAM HACKLY CHURCH, OF SUPERE, SASKATCHEWAN, CANADA.

SHOCKING MACHINE.

Application filed June 1, 1920. Serial No. 385,364.

To all whom it may concern:

Be it known that I, WILLIAM HACKLY CHURCH, of the town of Superb, in the Province of Saskatchewan, Canada, have 5 invented certain new and useful Improvements in Shocking Machines, of which the following is the specification.

The invention relates to improvements in shocking machines and particularly to a 10 shocking machine basket and the principal object of the invention is to improve the structure of the basket of the machine previously invented by me and as fully set forth and described in my prior application 15 No. 228,843 filed the 16th April, 1918, and in the following manner:—

To provide a head guard for the sheaves, to provide a means for effectively gripping and compressing the assembled sheaves in 20 the basket, thereby drawing their heads together and spreading their butts, such occurring during the initial dumping movement of the basket and to provide means to give the butt of the shock an inclined or 25 slanting base prior to depositing.

With the above more important objects in view the invention consists essentially in the arrangement and construction of parts hereinafter more particularly described and 30 later pointed out in the appended claims, reference being had to the accompanying drawings in which:—

Fig. 1 is a plan view of the shocker frame and the basket, the basket being in sheaf receiving position.

Fig. 2 is an end view thereof.

Fig. 3 is an enlarged detailed plan view of the basket.

Fig. 4 is an enlarged detailed side view 40 of the basket.

Fig. 5 is a vertical sectional view at 5—5', Figure 4 through the basket showing the pressure fingers in full outline in open position and in dotted outline in closed position.

Fig. 6 is a further vertical sectional view at 6—6', Figure 4 through the basket showing the pressure bars in full outline in open position and in dotted outline in closed position.

Fig. 7 is an enlarged vertical sectional view through the spring casing associated with the pressure fingers.

Fig. 8 is a front view of the pressure spring associated with the crank arm.

In the drawings like characters of reference indicate corresponding parts in the several figures.

As herein before intimated this invention relates to an improvement in the basket and whilst I have herein shown other parts of the shocking machine I have not considered it necessary to enlarge upon their description as those parts other than the basket herein shown are identical to those previously shown and described in my prior application numbered as above.

The sheaf receiving and shock forming basket 1 is pivotally suspended from the shocker frame 2 by a basket shaft 3 which passes under the basket more or less centrally of the length thereof and is suitably fastened thereto and has the ends projecting horizontally and mounted in suitable bearings 4, 5 and 6 provided on the shocker frame.

This arrangement is such that in the rotation of the basket shaft the basket is dumped. On the outer end of the shaft a ground wheel 7 is rotatably mounted and a suitable connection is provided for connecting the wheel to the shaft to effect the turning of the basket at a proper instant and for disengaging the wheel to allow it to turn free during the interval that the basket is being filled.

A butting plate 8 is located at the butt end of the basket, such being carried by the frame and the opposite sides of the basket carry rotatably mounted operating shafts 9 and 10 which are carried in suitable bearings secured to the edges of the basket. These shafts are fitted with outwardly extending cranks 9' and 10' which are designed to engage with striker plates 11 and 12 secured permanently to the shocker frame and extend downwardly in rearwardly curving guides 11' and 12'.

The latter arrangement is such that when the basket turns to dump the shock the cranks initially turn the shafts 9 and 10 and then hold the shafts in turned position for a period of time as controlled by the length of the guides.

The new features of my invention which relate specifically to the basket are now described in detail:—

At the head end of the basket I locate a head guard or hood 13 which is formed

from an upwardly arched bar 14 having the ends permanently secured at 15 to the sides of the basket and fillers 16 in the form of wires passing vertically from the bar 14 to the end of the basket. This head guard or hood prevents the sheaves from slipping endwise, lining them up so to speak.

Somewhat slightly in advance of the centre of the basket and crossing the same I 10 locate an upwardly extending somewhat inclined spacer plate 17 which is permanently secured in place and serves to form a rest or support for the sheaves deposited in the basket, the said plate engaging the sheaves approximately at the point where they are 15 customarily bound or tied.

Directly in advance of this spacer plate and at opposite sides of the basket I provide a pair of pressure fingers 18 and 19, the 20 fingers being pivotally mounted on pivot pins 20 and 21 provided on the basket bottom.

Here it is to be observed that these pressure fingers are slightly bowed in opposite 25 directions, the upper tips being out-turned to prevent impaling of the down-coming sheaf whilst the lower ends are projected through suitable slots provided in the bottom of the basket and form in each instance 30 a lever arm 22 which controls the movement of the finger. The lever arm of the finger 18 is connected by a link 23 passing cross-wise underneath the basket to a bell crank 24 pivotally mounted at the opposite side 35 of the basket and having the upper end thereof contained within the basket and connected pivotally at 25 to one end of a pressure jaw 26, the other end of which is pivotally connected at 27 to the lower part of 40 the finger 18 in a location within the basket and above the pivot 20.

The latter structure is duplicated in connection with the finger 19 and lever arm thereof, providing a second pressure jaw 28 45 within the basket corresponding to that 26. Both the pressure jaws lie normally in the bottom of the basket and are fitted with a series of upwardly extending prongs 29, the points of which are normally located below 50 the plane of the upper edge of the spacer plate.

To each of the shafts 9 and 10 I secure 55 permanently an outwardly extending crank 30 and the crank is connected to the lever arm of the adjacent pressure finger in each instance by a give and take connection embodying a spring casing 31 containing a compression spring 32, the compression spring operating between the upper closed 60 end of the casing and a plunger 33 located on a plunger rod 34 which extends upwardly through the top end of the casing and is connected to the end of the crank 30. The lower end of the casing is connected by a rod 65 35 to the adjacent lever arm 22. Adjusting

nuts 36 are provided on the rod 34 so that one can limit the inward or downward movement of the plunger. The shafts 9 and 10 are maintained normally in a position such that the crank ends 9' and 10' thereof 70 extend horizontally outwardly, this being accomplished by the action of a spring 37 mounted on each shaft and provided with extending legs 38 and 39 engaging the inner side of the basket and with a central upwardly extending part 40 which is engaged with a fixed arm 41 extending from the shaft. 75

When the cranks 9' and 10' are in the normal position as just explained the fingers 18 and 19 are open and the jaws 26 and 28 are down. However, upon the basket being dumped and the shafts 9 and 10 being rotated the cranks 30 are swung upwardly 80 in respect to the basket and in swinging upwardly pull the lever arms 22 upwardly and in so doing not only close the pressure fingers in around the contained shock but also raise the jaws 26 and 28 underneath the shock so that the shock is actually grasped 90 tightly and pressed between the fingers and the jaws, this all occurring in the initial dumping movement of the basket.

Here it is to be noticed that the prongs will pierce the shock and this together with the gripping action of the fingers and jaws 95 positively prevents the shock from slipping and being prematurely dropped on the ground.

Further it is to be observed that the arrangement provided allows the fingers and jaws to accommodate themselves to the size of the shock in the basket. For example, if the shock is a large one the full movement of the cranks 30 is provided for, as is also the 100 proper gripping of the shock by the fingers and jaws but as the movement of the fingers and jaws at this time is limited by the size of the shock the difference is taken up by a compression of the springs 31 in the casings. 105

On the other hand, if the shock is a comparatively small one there will be less compression in the springs 31 but otherwise all other movements are accommodated and without in the slightest altering the positive 110 and tight gripping of the shock by the jaws and fingers.

The location of the fingers and jaws is such that the heads of the sheaves are 115 squeezed more or less tightly together which results in the spreading of the butts of the sheaves and a consequent large butt to the shock which is a valuable feature.

At the time the shock is to be deposited, this occurring when the cranks 9' and 10' 120 escape from the lower ends of the curved extensions 11' and 12', it will be apparent that the fingers and jaws are released to open or return to their original position as obviously the instant the cranks 9' and 10' 125

clear from the extensions the main controlling springs 37 will act to return the shafts 9 and 10 to their original positions and in returning the shafts will effect the swinging 5 of the cranks 30 and the resultant opening of the jaws and fingers.

At the time of depositing the sheaf the spacer plate performs an important function, that is, it acts as a guard, holding the 10 shock clear of the prongs 29, the jaws in opening withdrawing so that they are not exposed beyond the inner edge of the spacer plate.

Within the rear part of the basket, that 15 is to say in a location to the rear of the spacer plate, I provide also a pair of pressure bars 42 and 43 which are similarly constructed, each being more or less of a U-shape. One end of each bar extends upwardly above the side of the basket and the other end is pivotally mounted to the opposite side of the basket as indicated at 44.

To each of the shafts 9 and 10 I secure 20 permanently a further pair of outwardly extending cranks 45 and 46, the crank 45 being connected by a link 47 to the adjoining upper part of the pressure bar 42 whilst the crank 46 is connected by a link 48 to the adjoining upper part of the pressure bar 43. 25 These pressure bars are normally open in the sheaf receiving and shock forming position of the basket and upon the initial dumping movement of the basket it will be obvious that the cranks 45 and 46 in swinging 30 upwardly will act through the links to move the pressure bars to a position such as shown in dotted outline in Fig. 6. In this position it will be seen that the lower parts of the pressure bars, whilst acting to 35 squeeze the sheaf together, act also to raise the shock as the under parts of the said bars have actually risen from the bottom of the basket. As the head of the shock is 40 already grasped by the pressure fingers and the jaws the raising movement of the bars 45 and 46 acts to slant or incline the bottom or base of the shock butt. Consequently 45 when the shock is subsequently deposited it drops on the inclined base and the momentum of the deposited shock does not upset 50 the shock but rather simply corrects the base so that the deposited shock stands in the upright position.

This is a very important feature as it 55 enables me to set up all shocks under normal conditions in a field.

Whilst I have described the various parts in detail it will be readily understood that the details thereof could be readily changed 60 without departing from the spirit of the invention as set forth in the accompanying claims.

What I claim as my invention is:—

1. In a horizontally disposed sheaf receiving and shock forming basket, means for

gripping and compressing the head of the contained shock and upwardly movable means underlying the butt end of the shock.

2. In a horizontally disposed sheaf receiving and shock forming basket, means for gripping and compressing the head of the contained shock and means underlying the butt end of the shock and designed to close around the butt end and at the same time raise the butt end. 70

3. In a horizontally disposed sheaf receiving and shock forming basket, a pair of normally open upwardly extending pressure fingers carried by the basket and located towards the head end of the contained shock, a pair of pressure jaws located in the bottom of the basket and underlying the shock and means for simultaneously raising the jaws and closing the fingers to grip and compress the head end of the shock. 75

4. In a horizontally disposed sheaf receiving and shock forming basket, a pair of normally open upwardly extending pressure fingers carried by the basket and located towards the head end of the contained shock, a pair of pressure jaws located in the bottom of the basket and underlying the shock, means for simultaneously raising the jaws and closing the fingers to grip and compress the head end of the shock and prongs extending upwardly from the jaws and extending into the shock. 90

5. In a horizontally disposed sheaf receiving and shock forming basket, a pair of normally open pressure fingers located towards the head end of the contained shock, a pair of pressure jaws within the basket and underlying the head of the shock and associated with the fingers, said fingers and jaws being arranged so that upon the fingers being closed inwardly the jaws rise 100 from the bottom of the basket. 105

6. In a horizontally disposed sheaf receiving and shock forming basket, a pair of normally open pressure fingers located towards the head end of the contained shock, said fingers being each separately pivoted to the basket and having their lower ends projecting through the bottom of the basket to provide lever arms, a bell crank pivotally mounted in the bottom of the basket, there being a bell crank opposing each pressure finger, cross links connecting the lever arms with the bell cranks a pair of pressure jaws within the basket and underlying the head of the shock, said jaws being connected pivotally to the bell cranks and to the pressure fingers and means for manipulating the lever arms at a predetermined instant to actuate the pressure fingers and jaws. 110 115

7. In a horizontally disposed sheaf receiving and shock forming basket, a pair of normally open pressure fingers located towards the head end of the contained shock, said fingers being each separately pivoted 120 125

to the basket and having their lower ends projecting through the bottom of the basket to provide lever arms, a bell crank pivotally mounted in the bottom of the basket, there being a bell crank opposing each pressure finger, cross links connecting the lever arms with the bell cranks, a pair of pressure jaws within the basket and underlying the head of the shock, said jaws being connected pivotally to the bell cranks and to the pressure fingers, an operating rod rotatably mounted on each side of the basket, means for turning the rods in the dumping of the basket, a crank extending from each rod, a give and take connection between the cranks and the lever arms and spring means normally maintaining the levers in a set initial position.

8. In a horizontally disposed sheaf receiving and shock forming basket, coacting

pressure fingers and jaws located and manipulated to grasp the head end of the contained shock and compress and hold the same, the said jaws underlying the shock and a spacer plate crossing the basket and underlying the shock and spacing it from the bottom of the basket and located adjoining the jaws and behind which the jaws retract when released from the shock.

9. A device as set forth in claim 3, including means for holding the shock clear of the pressure jaws when the latter are disposed in inoperative position as in forming the shock.

Signed at Winnipeg, this 14 day May 35 1920.

WILLIAM HACKLY CHURCH.

In the presence of:—

G. S. ROXBURGH,
K. B. WAKEFIELD.
